UNITED STATES PATENT OFFICE.

JOHN HARTMAN, JR., OF ORMSBY, PENNSYLVANIA.

DESIGN FOR A BADGE.

Specification forming part of Design No. 5,927, dated June 11, 1872.

Specification describing a certain Design for a Badge, invented by JOHN HARTMAN, Jr., of Ormsby Borough, Allegheny county, and State of Pennsylvania.

The nature of my design is fully represented in the accompanying drawing, to which reference is made.

A represents the upper part of my design, shaped in the form of a scroll, upon which are inscribed the initial letters of the title of the society aforesaid. B represents a grape-leaf, which constitutes the lower part of my design, engraved and shaped as represented in the

drawing. C represents the links connecting the scroll with the leaf; the whole forming insignia to be worn as a badge by the members of the said society.

What I claim as my invention is—

A design for a badge, which is composed of the scroll A and the leaf B, connected by the links C, engraved substantially in the manner above described.

JOHN HARTMAN, JR.
